UNITED STATES PATENT OFFICE.

CHARLES G. CURTIS, OF NEW YORK, N. Y., ASSIGNOR, BY MESNE ASSIGNMENTS, TO CURTIS STEAM TURBINE COMPANY, A CORPORATION OF WEST VIRGINIA.

ELASTIC-FLUID TURBINE.

SPECIFICATION forming part of Letters Patent No. 700,744, dated May 27, 1902.

Application filed January 12, 1898. Serial No. 686,379. (No model.)

To all whom it may concern:

Be it known that I, CHARLES G. CURTIS, a citizen of the United States, residing at New York city, in the county and State of New York, have invented a certain new and useful Improvement in Elastic-Fluid Turbines, of which the following is a specification.

My invention relates to an improvement upon governors for elastic-fluid turbines involving the invention described and claimed in my Patent No. 566,967, wherein regulation is effected without material loss of efficiency by varying the volume of the elastic fluid without substantial variation of its velocity at the point or points where it acts upon the movable elements or vanes of the turbines. It involves among other features an improvement in the device shown in Figure 6 of said patent—namely, a partitioned nozzle having more or fewer of its divisions or sections closed or opened as the load decreases or increases.

In carrying out my invention I employ a form of delivery-nozzle in which the nozzle is divided up into a number of separate sections, and these separate sections are brought together in a single structure or made into a single casting with their discharging ends approximated so closely that the fluid is delivered by the several sections to the buckets in the form of a substantially solid body or stream. These sections are preferably substantially alike in form and in angle of delivery, each section having a throat and walls leading from said throat to the discharging end of the nozzle, which walls may or may not afford an enlarging cross-section of passage, according to the degree of conversion of pressure into *vis viva* desired. The nozzle-sections are also preferably provided with separate enlarged supply-chambers anterior to the throats. Separate steam passages or pipes extend from the sections of the nozzle back to a connection with the steam-boiler or other source of elastic fluid under pressure, and these passages I make controllable by means of a valve or valves, so as not only to vary the number of sections receiving the elastic fluid, but to throttle and regulate the flow through a single section acting in conjunction with other full sections. These passages are preferably all

extended to a valve-case, and the number of sections of the nozzle in operation is determined by a valve, preferably moved by a speed-governor. This valve in moving across the ports connected with the sections of the nozzle will progressively open or close the ports in succession, so that at no time will more than one section of the nozzle be throttled with reference to the fluid-supply, and thus permit expansion of the fluid under inefficient conditions in that section; but I have found that with a nozzle composed of a number of sections this loss of efficiency is only a small percentage of the entire *vis viva* developed, and hence the velocity of the elastic-fluid body as a whole will be maintained without substantial variation during the gradual changes in its volume or quantity which are effected by the valve progressively opening or closing the sections of the nozzle. By controlling the flow of steam in this manner I am enabled to obtain quite a high average efficiency under a widely-varying load even with only a few sectional divisions of the nozzle, because under all conditions except those of very small load a number of the sections will be operating at their maximum efficiency and only one of the sections can be working with a lower efficiency. In other words, the total *vis viva* developed in the nozzle is produced by a number of sections working at full efficiency and perhaps one additional one working with an efficiency which varies in accordance with the slight changes in power; but it will be observed that where the additional section is doing but a slight amount of work and working at comparatively low efficiency the work contributed by it to that of the other sections is such a small fraction of the whole that a considerable sacrifice in efficiency of this section causes an unimportant reduction in the efficiency of the nozzle as a whole. Similarly while this additional section is working at a considerable fraction of its full capacity its efficiency is quite high, so that by more or less throttling only one of the sections at a time I am enabled to obtain a close regulation with quite a high average efficiency under all conditions except those of very light load. By increas-

ing the number of sections, which of course can be done indefinitely, a more uniform efficiency may be obtained, particularly with very small fractional loads.

5 My improved sectional nozzle is especially applicable to a jet-turbine or one in which the elastic fluid is discharged in the form of a jet to a part only of the circumference of the turbine wheel. It is, however, also applicable to elastic-fluid turbines of that class in which the ring of buckets receives the elastic fluid simultaneously throughout its entire circumference when developing its maximum power, a portion only of the ring of buckets 10 receiving fluid when less than the maximum power is being developed. In such a case the nozzle will occupy the entire circumference of the turbine and be divided into any desired number of sections, and the independent passages from the sections of the nozzle to the source of supply may be controlled by hand or automatic valves or partly by hand-valves and partly by automatic valves. The separate sections composing the complete sectional nozzle may all be of the same size or of 15 different sizes, but should be of like form. I have applied my improved sectional nozzle also to my multiple-stage elastic-fluid turbine, wherein the movable vanes are divided between two or more shells working at different 20 initial pressures, as described in my Patent No. 566,969, as well as to arrangements for operating the same turbine (whether having one shell or two or more shells) either as a condensing or non-condensing engine.

35 My improved sectional nozzle has the advantage over the divided nozzle shown in Fig. 6 of my Patent No. 566,967 in that by making a sectional nozzle composed of a number 40 of independently-complete sections all alike the length of the walls from the throat to the discharging end of the nozzle is greatly diminished and the loss from surface friction is lessened, and, further, the improved sectional nozzle is provided with a more practical and simple, and therefore more desirable, form of valve mechanism. In my improved sectional nozzle the loss from surface friction is also lessened, because at each cross- 45 section at or near the throat of the nozzle a form may be adopted which will give a lower ratio of perimeter to cross-sectional area than is possible in the form of construction shown in Fig. 6 of my Patent No. 566,967. This will 55 reduce the total surface exposed to the fluid. By making the cross-section of the throat a circle, as shown in some of the drawings herein, I am enabled to obtain a minimum of surface exposed as compared with the volume or 60 quantity of steam and a better throat action is also secured, thus affording a more satisfactory device for converting pressure into *vis viva*. It will be observed, however, that in this improved sectional nozzle, as in the 65 divided nozzle of the patent referred to, the elastic fluid is discharged from the several sections of the nozzle as a practically continu-

ous body or stream. If the discharge ends of the sections of the nozzle were separated or if the turbine had several separated nozzles, the stream issuing from each section or from each nozzle would inadequately fill the two buckets exposed to it at the ends of its side walls, thus causing inefficient action in these two buckets. This loss of efficiency would be 75 multiplied by the number of separated sections or separate nozzles, but is reduced to a minimum by bringing the ends of the sections close together and separated each from the other by a thin partition only, the columns of fluid on the two sides of each partition uniting as they leave the edge to form a solid body or stream of fluid, the thin partitions causing no gaps between the several sections of the stream. This feature becomes very important in a jet-turbine, and its 80 importance increases as the working passage is more and more compounded.

In the accompanying drawings, forming a part hereof, Fig. 1 is a horizontal section showing my improved sectional nozzle applied to a compound jet-turbine, such as that of my Patent No. 566,968. Fig. 2 is an elevation illustrating the discharging end of the nozzle. Fig. 3 is an outline sketch illustrating on a larger 95 scale the form of one of the nozzle-sections composing the sectional nozzle. Fig. 4 is a sectional view through two of the nozzle-sections on the line 4-4 in Fig. 1 and looking in the direction of the arrow at that line. Fig. 100 5 is a vertical section following the line of one of the steam-passages. Fig. 6 is a horizontal section illustrating the invention applied to a double-shell jet-turbine, such as that of my Patent No. 566,969. Fig. 7 is a 105 plan view of the construction illustrated in Fig. 6. Fig. 8 is a horizontal section of my improved nozzle applied to a turbine adapted to operate either as a condensing or a non-condensing engine, such as is described in my 110 Patents Nos. 589,466 and 590,210, the ports in the governing-valve being arranged at right angles to those of the valve shown in Fig. 1. Fig. 9 is a partial end view showing the improved sectional nozzle applied to a turbine whose entire circumference is utilized for the admission of the elastic fluid. Fig. 115 10 is a view in outline in which the sectional nozzle of Fig. 9 is partly developed in a horizontal plane; and Fig. 11 is an end view of the discharging-nozzle of Fig. 9, all sections of the nozzle being of the same size.

Referring particularly to Figs. 1 to 5, inclusive, A is the shell of the turbine, in which rotates a wheel B, carrying one or more sets 125 of movable vanes C' (two being herein shown also) and a set of stationary intermediate vanes C², as will be understood by reference to my prior patents. D is the exhaust-port 130 of the turbine, opening directly into the air or connected with a condenser. Secured in an opening in the shell, so as to deliver a jet of elastic fluid to the first set of vanes C, is a cored casting E, forming my improved sec-

tional nozzle. This is composed of a number of short sections F, provided with contracted throats a and having supply-chambers larger than the throats anterior thereto and with 5 walls which converge to form the throats and also having posterior to the throats diverging walls which extend to the discharging ends of the sections, at which points the separating-walls are made so thin that the elastic 10 fluid unites when discharged from the several sections and forms a practically continuous body. Attached to the casting E or made integral with it is another casting G, carrying a number of steam-passages F', one for each 15 of the nozzle-sections F, which steam-passages extend back to the ports b in the valve-case H. The valve-case H is provided with a closing-casting H' and with heads c. These parts E, G, and H being all castings may be divided 20 at any suitable points into any desired number of parts to secure cheapness and perfection in manufacture. The passages F' start with the oblong ports b of rectangular form and are of sufficient area to permit the de- 25 sired quantity of fluid to flow without objectionable loss of pressure, and the passages beyond are also made large enough so as to cause no loss in pressure and gradually become of circular cross-section, which is main- 30 tained up to the contracted throat a of the nozzle-sections, as illustrated in Fig. 4, and from the throat the sections are gradually drawn into a rectangular form toward their discharging ends, increasing in cross-section 35 from the throats to the discharging ends, so as to give a further expansion of the elastic fluid and a further conversion of pressure into velocity. If the nozzle is one having no expansion—that is, no enlargement in cross- 40 sectional area from the throat to the discharging end—then the throat must either be made of a rectangular form having the same area as the rectangular end of the nozzle, or if the throat be circular in form its diameter must 45 be such as to give an area equal to the area of the rectangular discharging end of the nozzle. Back of the throat a the passages F' should theoretically have the form illustrated by the dotted lines in Figs. 3 and 4; but 50 since by giving them this form one passage would encroach upon another the lower wall of each passage is slightly flattened, as illus- 55 trated by the full lines. Within the valve-case H is the valve I, having two circular heads or pistons d d', which are always on opposite sides of the steam-inlet J, and hence 60 balance the valve. The head d plays across the ports b and has an angular or oblique face where it rides over the ports, as illus- 65 trated in Fig. 8, so that at the instant of completely closing or opening one port it begins to close or open the next port if moved farther in the same direction. The ends of the valve-case outside of the heads of the 70 valve are connected together by a passage e and may be connected with the shell of the turbine by a pipe f, so that any leakage past

the heads will be carried into the shell of the turbine, thus maintaining the same pressure on the outer sides of both heads of the valve. 70 The valve-stem I' extends outwardly through one head of the valve-case and may be operated by hand, but is preferably connected with a speed-governor for operating the valve automatically. The pipe f may be omitted, 75 if desired, and the valve so arranged that any leakage will find its way into the shell through the nozzle-passages.

Referring particularly to Figs. 6 and 7, showing a compound double-stage turbine, as 80 described in my Patent No. 566,969, A and A' are two shells, each containing one or more sets of movable vanes, two sets in each shell being illustrated. One of my improved sectional nozzles and controlling-valves is con- 85 nected with each shell, the valve-case for controlling the sectional nozzle of the second shell having its inlet-pipe connected with the exhaust of the first shell. The two valve- 90 stems I I' are operated simultaneously by the same speed-governor K by means of a lever g, connected by links h h' with bell-cranks i i', which are proportioned to give the two valves proportionate movements, the valve controlling the nozzle to the second shell be- 95 ing larger and requiring a greater length of movement, due to the fact that the steam or other elastic fluid has a lower pressure and a greater volume where it enters the valve-case of the second shell than it does when enter- 100 ing the valve-case of the first shell. If the first stage be worked with an exhaust of ap- 105 proximately atmospheric pressure, provision may be made for connecting this exhaust to the atmosphere, as illustrated in dotted lines 110 in Fig. 6, so as to utilize the method of work- 115 ing the turbine either as a condensing or non- condensing engine, which is described specif- 120 ically in my Patent No. 590,211. Under such conditions the volume of the steam will be, 125 roughly speaking, nine times greater at the second valve-case than at the first valve-case, and with the enlarged construction which this increased volume requires the second controlling-valve may have a movement three 130 times as great as the first controlling-valve. These proportions are intended to be illus- 135 trated in Figs. 6 and 7.

In Fig. 8 I have shown a single shell A, provided with a wheel B, having two sets of 140 movable vanes C C' and having two sets of intermediate stationary passages C² C³, which operate in conjunction with two of my im- 145 proved sectional nozzles L L' and two ex- haust-ports D D'. The nozzle L is adapted to 150 give the elastic fluid that degree of ex- pansion which is required for working the tur- 155 bine as a condensing-engine, while the nozzle L' gives a lower degree of expansion, such as 160 is required for working the turbine as a non- condensing engine, the intermediate passages C² and C³ being also properly proportioned, 165 as described in my Patent No. 590,210. The valve-case H has a single set of ports b, which

are connected with the passages extending to both nozzles, and these passages are provided with hand-operated valves M for opening and closing them, so that the passages leading to one of the sectional nozzles may be closed while the other nozzle is in operation.

It is evident that the constructions illustrated in Figs. 1 to 8, inclusive, could all be employed in the same turbine. The separation of the illustrations is made to avoid confusion.

Referring particularly to Figs. 9, 10, and 11, the sectional nozzle is illustrated as one which occupies the entire circumference of the turbine, and when all the sections of the nozzle are opened and the turbine is developing its maximum power the elastic fluid is delivered simultaneously throughout the entire circumference of the turbine. The several sections F meet at their discharging ends, or substantially so, in order that the elastic fluid delivered by two adjacent sections of the nozzle may unite into a continuous body of fluid at the point of discharge from the nozzle. The separate sections of the nozzle are connected with the common steam-supply pipe N and are controlled by hand-valves O, which may be operated automatically, if desired. The sections may be made of different sizes, as is indicated in the drawings, where the sections F² are of smaller size.

I also propose to use my improved sectional nozzle in the elastic-fluid compressor upon which I have applied for a patent, (application Serial No. 601,606.)

What I claim is—

1. The sectional nozzle for elastic-fluid turbines herein described, consisting of a number of separate complete nozzle-sections each having a contracted throat, and a supply-chamber anterior to and larger than said throat, such sections being brought close together at their discharge ends, whereby the several separate jets or streams merge into a substantially single jet or stream at the points of discharge, substantially as set forth.

2. The sectional nozzle for elastic-fluid turbines herein described, consisting of a number of separate complete nozzle-sections each having a contracted throat, a supply-chamber anterior to and larger than said throat, and a discharging portion posterior to said throat, said sections being brought close together at their discharge ends, whereby the several separate jets or streams merge into a substantially single jet or stream at the points of discharge, substantially as set forth.

3. The sectional nozzle for elastic-fluid turbines herein described, consisting of a number of separate complete nozzle-sections each having a contracted throat, a supply-chamber anterior to and larger than said throat, and a discharging portion posterior to and enlarging beyond said throat, such sections being brought close together at their discharge ends, whereby the several separate jets or streams merge into a substantially single jet or

or stream at the points of discharge, substantially as set forth.

4. In an elastic-fluid turbine, a sectional nozzle consisting of a number of separate complete nozzle-sections each having a contracted throat, a supply-chamber anterior to and larger than said throat, and a discharging portion posterior to and enlarging beyond said throat, such sections being brought close together at their discharge ends, whereby the several separate jets or streams merge into a substantially single jet or stream at the points of discharge, in combination with means for admitting the elastic fluid to or shutting it off from more or less of said nozzle-sections, substantially as set forth.

5. In an elastic-fluid turbine, a sectional nozzle consisting of a number of separate complete nozzle-sections each having a contracted throat, a supply-chamber anterior to and larger than said throat, and a discharging portion posterior to and enlarging beyond said throat, such sections being brought close together at their discharge ends, whereby the several separate jets or streams merge into a substantially single jet or stream at the points of discharge, in combination with a number of separate supply-passages, a valve-case with ports for such separate passages, and a valve in such valve-case opening and closing said ports progressively, substantially as set forth.

6. In an elastic-fluid turbine, a delivery-nozzle comprising sections substantially alike in form and in angle of delivery and brought close together at their discharge ends, whereby the jets or streams from adjacent sections merge into a substantially single jet or stream at the points of discharge, in combination with means for admitting the elastic fluid to or shutting it off from more or less of said sections, substantially as set forth.

7. In an elastic-fluid turbine, a delivery-nozzle comprising sections substantially alike in form and in angle of delivery and brought close together at their discharge ends, whereby the jets or streams from adjacent sections merge into a substantially single jet or stream at the points of discharge, in combination with a plurality of separate supply-passages extending back from said nozzle-sections, and means for admitting the elastic fluid to or shutting it off from more or less of said supply-passages, substantially as set forth.

8. In an elastic-fluid turbine, the combination with two or more shells having movable vanes and receiving the elastic fluid in succession, of a delivery-nozzle for each shell comprising sections substantially alike in form and in angle of delivery and brought close together at their discharge ends, whereby the jets or streams from adjacent sections merge into a substantially single jet or stream at the points of discharge, valves for admitting the elastic fluid to or shutting it off from more or less of the sections of each nozzle, and means for moving said valves coördinately, substantially as set forth.

9. In an elastic-fluid turbine, the combination with two or more shells having movable vanes and receiving the elastic fluid in succession, of a delivery-nozzle for each shell comprising sections substantially alike in form and in angle of delivery and brought close together at their discharge ends, whereby the jets or streams from adjacent sections merge into a substantially single jet or stream at the points of discharge, a plurality of separate supply-passages extending back from the sections of said nozzle, valves for admitting the elastic fluid to or shutting it off from more or less of the supply-passages of each nozzle, and means for moving said valves coördinately, substantially as set forth.

10. In an elastic-fluid turbine, the combination with two or more shells containing movable vanes and receiving the elastic fluid in succession, of delivery-nozzles of successively-greater cross-sectional area for the two or more shells, each of such delivery-nozzles comprising sections brought close together at their discharge ends, a plurality of supply-passages for the sections of each nozzle, valve mechanisms acting to open and close such supply-passages, such valve mechanisms having successively a greater movement for the same degree of regulation, and means causing the valve mechanisms to work coördinately so that the two or more nozzles shall be proportionately opened and closed, substantially as set forth.

11. In an elastic-fluid turbine, the combination of a number of separate supply-passages and separate complete nozzle-sections proportioned for the degree of conversion of pressure into velocity required for condensing-work, and a number of separate supply-passages and separate complete nozzle-sections proportioned for the degree of conversion of pressure into velocity required for non-condensing work, and valves for closing the supply-passage to one set of nozzle-sections when the supply-passages to the other set of nozzle-sections are opened, substantially as set forth.

12. In an elastic-fluid turbine, the combination of a number of separate supply-passages and separate complete nozzle-sections proportioned for the degree of conversion of pressure into velocity required for condensing-work, and a number of separate supply-passages and separate complete nozzle-sections proportioned for the degree of conversion of pressure into velocity required for non-condensing work, valves for closing the supply-passages to one set of nozzle-sections

when the supply-passages to the other set of nozzle-sections are opened, and a governing or controlling valve common to the supply-passages of both sets of nozzle-sections for controlling the admission of elastic fluid to the set of nozzle-sections in operation, substantially as set forth.

13. In an elastic-fluid turbine, a delivery-nozzle comprising a number of sections brought close together at their discharge ends, each having a throat and diverging side walls beyond the throat, such side walls being formed by partitions separating the sections which are thicker at the throats than at the discharge ends of the sections, substantially as set forth.

14. In an elastic-fluid turbine, separate supply-conduits leading from a source of fluid-supply under pressure to two or more expansion delivery-passages delivering the fluid to the same set of buckets, in combination with valve mechanism automatically actuated by a speed-governor for admitting the fluid to and excluding it from the supply-conduits in succession, the valve mechanism opening and closing each conduit successively by degrees, substantially as set forth.

15. In an elastic-fluid turbine, a nozzle the cross-sectional perimeter of whose throat is curved, said nozzle having a rectangular discharging end in combination with a rotating turbine-wheel, substantially as set forth.

16. In an elastic-fluid turbine, a nozzle whose throat has a curved cross-sectional perimeter and having expanding or diverging walls which gradually draw into a rectangular form at the discharging end of the nozzle, substantially as set forth.

17. In an elastic-fluid turbine, a sectional nozzle, the throats of the several sections having a curved cross-sectional perimeter, and the discharge ends being rectangular, in combination with a rotating turbine-wheel, substantially as set forth.

18. In an elastic-fluid turbine, a sectional nozzle, the throats of the several sections having a curved cross-sectional perimeter and opening into expansion delivery-passages whose diverging walls gradually draw into a rectangular form at their discharge ends, substantially as set forth.

This specification signed and witnessed this 7th day of January, 1898.

CHARLES G. CURTIS.

Witnesses:

EUGENE CONRAN,
JNO. R. TAYLOR.

It is hereby certified that in Letters Patent No. 700,744, granted May 27, 1902, upon the application of Charles G. Curtis, of New York, N. Y., for an improvement in "Elastic-Fluid Turbines," an error appears in the printed specification requiring correction, as follows: In line 21, page 1, the word "lead" should read *load*; and that the said Letters Patent should be read with this correction therein that the same may conform to the record of the case in the Patent Office.

Signed and sealed this 3d day of June, A. D., 1902.

[SEAL.]

F. I. ALLEN,
Commissioner of Patents.
